QUICK RESET INDUCTION DISK RELAY

Max Rigert, West Allis, Wis., assignor to McGraw-Edison Company, Milwaukee, Wis., a corporation of Delaware
Filed May 9, 1960, Ser. No. 27,585
2 Claims. (Cl. 317—58)

This invention relates to protective devices and, more particularly, to a time delay relay having particular but not exclusive application to repeating circuit interrupters.

Repeating circuit interrupters or reclosers are often employed in a main distribution line adjacent the source of power and wherein feeder lines radiating from the main line are protected by fuses. Because the majority of faults in distribution systems are temporary in nature and will clear in a relatively short time, repeating circuit interrupters or reclosers protecting such systems are commonly designed to execute a series of rapidly successive opening and reclosing operations upon the occurrence of a fault, so that the period during which the system remains energized is shorter than that necessary for the fuse elements to melt. If the fault has not cleared after a predetermined number of such operations, they are followed by a second series of operations in which the interrupter contacts remain closed for a sufficient length of time to melt the fuse elements. If the fault has not cleared after this second group of operations it is considered permanent, and is then isolated from the source by lockout means operable to lock the recloser's contacts in an open position until manually or electrically reset.

The time between successive time delayed operations of a repeating circuit interrupter of this type is usually on the order of one to two seconds. Such delayed operations are accomplished by time delay means which remain inactive during the initial series of operations and which are made active to retard opening of the switch contacts during the second period of operations. One type of time delay device, an induction type relay, has been unsuitable for use in a repeating circuit interrupter because of its inherent inability to be reset between opening operations which renders rapidly successive operations impossible.

It is an object of the invention to provide an induction type time delay relay which is usable in a repeating circuit interrupter.

It is another object of the invention to provide an induction type relay which may be rapidly reset. It is yet another object of the invention to provide such induction type relays with means for rapidly resetting their contacts regardless of the position of the induction plate.

These and other objects and advantages of the invention will become more apparent in the detailed description of the invention taken in view of the accompanying drawing which schematically illustrates an induction type relay incorporating the instant invention.

In general terms, the invention comprises an induction relay having electromagnet means, an operating disc, contact means and releasable coupling means operable upon the energization of the electromagnet means to couple the contact means to the operating disc so that the contact means is moved toward its closed position. The coupling means is also operative upon the de-energization of the electromagnet means to release the contact means for rapid movement to its initial position whereby the device is reset. When used in a recloser the electromagnet means is in circuit with the system being protected and its de-energization occurs when the contact means closes to complete an energizing circuit to the recloser's switch opening means.

Referring now to the drawing in greater detail, an in-

2

duction type relay 10, according to the instant invention, is shown incorporated in a repeating circuit interrupter

12. The details of circuit interrupter 12, which forms no part of the instant invention, are shown in Patent No. 2,804,521 to A. Van Ryan et al. Relay 10 is coupled to the three phase system 14, which is being protected, by means of a three phase current transformer 16. Upon the occurrence of an unbalanced condition in system 14, such as a ground fault in one of the phases, operation of induction relay 10 is initiated and, in addition, a coupling and reset assembly 20 automatically couples it to the contact assembly 18. If the fault persists for a predetermined length of time, the contact assembly 18 will be closed, thereby energizing the trip coil 21 of repeating circuit interrupter 12 to open its main switch assembly 22. Upon this event, induction relay 10 is de-energized and the coupling and reset assembly 20 automatically returns the contact assembly 18 to its initial position in preparation for another operation. Means, not shown but which are well known in the art, are also provided for bypassing the time delay induction relay 10 during the initial series of rapid operations.

More specifically, the induction relay 10 is shown to include an operating disc 23 and an electromagnet assembly 24 having a laminated core 25 which includes pole pieces 26 and 27 and an exciting coil 28 wound on core 25 and connected to the neutral 29 of the three phase current transformer 16. Operating disc 23 is affixed to a shaft 30 for rotation in the air gap separating the pole pieces 26 and 27 of electromagnet 24. In addition, a retarding or damping magnet 31 is disposed with its pole pieces on either side of operating disc 23 to impart the desired time delay thereto. It will be understood that the speed at which operating disc 23 rotates will be governed by the strength of permanent magnet 31 and the flux density in the air gap between pole pieces 26 and 27 of electromagnet 24 which, in turn, is proportional to the magnitude of the unbalance current in system 14.

The contact assembly 18 includes a movable contact rod 32 rotatably mounted on shaft 30 by means of a bracket member 33 journaled on said shaft. In addition, a stationary contact 34 is mounted on a guide frame 35 having an arcuate slot 36 for receiving the upper end of contact rod 32 and for guiding it into engagement with fixed contact 34. The fixed and movable contacts 32 and 34 respectively are shown in conjunction with auxiliary circuitry illustrating how the induction relay 10 may be incorporated in repeating circuit interrupter 12. This auxiliary circuitry includes an energizing circuit for the trip coil 21 of circuit interrupter 12 which is completed between terminals 37 and 38 of a power source when the movable contact rod 32 engages the fixed contact 34. Energizing current for trip coil 21 then flows through the circuit defined by conductors 40 and 41, the coil 42 of a holding relay, conductor 44, the movable contact rod 32, the stationary contact 34, and conductors 45, 46 and 48.

The coupling and reset assembly 20 includes a ratchet 52 affixed to shaft 30 and a pawl 54 rotatably mounted adjacent ratchet 52 on a bearing post 56 secured to the bracket member 33. A spring 57 extending between pawl 54 and the movable contact rod 32, normally holds said pawl out of engagement with ratchet 52. The assembly also includes a coupling relay 58 having a magnetic core 60 and an armature 62. A nylon cord 63, which passes around a reduced portion of shaft 30 connects armature 62 to the pawl 54. It can be seen, therefore, that when current traverses the coil 65 of coupling relay 58, its armature 62 will pivot in a clockwise direction to move the nylon cord 63 toward the right and rotate pawl 54 against the influence of spring 57 and into engagement

3

with the teeth of ratchet 52. This provides a rigid connection between the movable contact rod 32 and the operating disc 23 so that rotation of the latter will move contact rod 32 in slot 36 toward the stationary contact 34. It can be seen, too, that this movement of stationary contact 32 will be against the restoring force of a torsion spring 67.

Should coil 65 become de-energized at any time, either before or after contact rod 32 engages stationary contact rod 34, spring 57 will rotate pawl 54 out of engagement with the teeth in ratchet 52 thereby freeing bracket 33 and the movable contact rod for rotation to their initial positions under the influence of torsion spring 67. It can be seen, too, that restoration of the contact rod 32 to its initial or starting position is independent of the movement of operating disc 23. Therefore, the damping effect of permanent magnet 31 on operating disc 23 has no effect upon the resetting time of contact assembly 18. Hence, the contact assembly 18 may be immediately reset upon the de-energization of coil 65, even though the operating disc 23 remains in its rotated position.

Referring again to the auxiliary circuitry associated with induction relay 10, a relay 69 is provided having a coil connected in the secondary 29 of three phase current transformer 16 and normally open contacts 70 in circuit between the coil 65 of coupling relay 58 and the source terminals 37 and 38.

From the foregoing discussion it will be apparent that when a ground fault occurs in one of the phases of the system 14 relay 69 will become energized to close its normally open contacts 70 and place the coil 65 of coupling relay 58 in circuit with the source terminals 37 and 38. This will rotate armature 62 in a clockwise direction from its phantom position to its position shown in full so that the nylon cord 63 will operate to rotate pawl 54 into engagement with the teeth in ratchet 52. Simultaneously the coil 28 of electromagnet 24 will also be energized so that its operating disc 23 will begin rotating in a clockwise direction as shown in the drawing. Because the bracket 33 is now coupled to the shaft 39, the operating rod 32 will begin moving in slot 36 toward the stationary contact 34. In this manner the movable contact rod 32 is coupled to the shaft 39 whenever the operating disc 23 rotates.

Should the ground fault disappear before the contact rod 32 engages the stationary contact 34, relay 69 will drop out thereby de-energizing the coupling relay 58 so that spring 57 disengages pawl 54 from ratchet 52 whereby the torsion spring 67 is free to return the contact rod 32 to its initial position. In addition, coil 28 will also be de-energized so that the rotation of operating disc 23 ceases.

On the other hand, should the ground fault persist until contact rod 32 engages the stationary contact 34, the circuit through the trip coil 23 of repeating circuit interrupter 12 is completed. Upon this event, latch 76 will be rotated out of engagement with the main contacts 22 allowing them to be opened under the influence of an opening spring 77. Each time the contacts 22 open, the coil 28 of electromagnet 24 becomes de-energized so that its operating disc 23 ceases to rotate. In addition, relay 69 drops out to de-energize the coil 65 of coupling relay 58 enabling springs 57 and 68 to move pawl 54 out of engagement with ratchet 52 so that the contact rod 32 may return to its initial position under the influence of torsion spring 67.

The engagement of contacts 32 and 34 also energizes relay 42 which is then operative to close normally open contacts 74 and thereby complete a by-pass circuit around contacts 32 and 34. This relieves the contact assembly 18 from carrying current during the operation of circuit interrupter 12.

When the main switch means 22 reaches its fully open position a bridging bar 79 will close normally open contacts 80 to place the reclosing coil 81 of circuit interrupter

12 in circuit between two phases of the system 14. As a result, an armature 82 coupled to the main switch means 22 is attracted upwardly against the influence of opening spring 77 thereby reclosing the main contacts 22 and resetting latch 76. If the ground fault has disappeared while the main switch means 22 was open, the current in the secondary 29 of current transformer 16 will again be zero and relay 69 and electromagnet 24 will remain de-energized. However, should the fault reappear, the unbalance in three phase current transformer 16 will again produce a current in its secondary 29 to energize the relay 69 and the coil 28 of electromagnet 24. As a result, induction relay 10 will begin another timing operation which results in tripping of the repeating circuit interrupter 12 in the manner described above. If the fault persists after a predetermined number of such opening and reclosing operations, usually three, the fault will be considered permanent and lockout means (not shown but which are well known in the art and which are shown in the above cited patent) will operate to prevent the reclosure of main switch means 22 until manually reset.

Trip coil 21 is also operative upon being energized, and simultaneously with the tripping of latch 76, to open contacts 84 so that said trip coil is not required to carry energizing current during the entire opening operation. It will be understood that contacts 84 will be closed when the main switch means 22 is relatched.

The time lapse between the opening and reclosing of contacts 22 is in the order of one second. As a result, the induction relay 10 must be reset for another operation within this time. In other words, movable contact 32 must return to its initial position while contacts 22 are open so that the time required for it to traverse slot 36, should a fault reappear after the reclosure of contacts 22, will be the same for each succeeding operation. This is readily achieved because movable contact 32 is reset independently of operating disc 23.

While only a single embodiment of the invention is shown and described, other modifications thereof will become apparent once the inventive concept is known. It is intended, therefore, to cover in the appended claims all such modifications that fall within the true spirit of the invention.

I claim:

1. In an induction relay, an electromagnet having an air gap and an exciting coil in circuit with an electrical system, a shaft rotatably mounted adjacent said electromagnet, an operating disc mounted on said shaft for rotation therewith and extending into said air gap, a damping magnet associated with said operating disc, said electromagnet being energizable upon the occurrence of a predetermined circuit condition to rotate said operating disc, coupling means including a ratchet affixed to said shaft and rotatable therewith, and bracket means rotatably mounted on said shaft, a pawl rotatably mounted on said bracket means about an axis parallel to said shaft, fixed and movable contact means, said movable contact means being mounted on said bracket means, electroresponsive means connected to said system and operative upon the occurrence of said circuit condition to rotate said pawl into engagement with said ratchet whereby said movable contact is connected to said operating disc for movement therewith from an initial position toward said fixed contact, said electroresponsive means being operative to release said pawl and said movable contact upon the disappearance of said circuit condition, and biasing means for rotating said pawl out of engagement with said ratchet and for returning said bracket means and said movable contact to their initial position.

2. In an induction relay, a core and an exciting coil in circuit with an electrical system, an operating disc mounted for rotation in accordance with the excitation of said coil, bracket means rotatably mounted adjacent said disc and independently thereof, coupling means including

ratchet means and coating pawl means, one of said ratchet and pawl means being affixed to said disc and the other being mounted on said bracket means, fixed and movable contact means, said movable contact means being mounted on said bracket means, electroresponsive means coupled to said system and operative upon the occurrence of a predetermined circuit condition to move said pawl means into operative engagement with said ratchet means whereby said movable contact is coupled to said operating disc for movement therewith from an initial position toward said fixed contact, said electroresponsive member being operative to release said pawl means and uncouple said movable contact from said operating disc upon the disappearance of said circuit con-

dition, and biasing means for moving said pawl means out of engagement with said ratchet means and for returning said bracket means and said movable contact to their initial positions.
